United States Patent Office.

JAMES M. FORD, OF BROOKLYN, NEW YORK.

Letters Patent No. 98,365, dated December 28, 1869.

IMPROVED SASH-CORD GUIDE-BLOCK

The Schedule referred to in these Letters Patent and making part of the same.

To all whom it may concern:

Be it known that I, JAMES M. FORD, of Brooklyn, in the county of Kings, and State of New York, have invented a new and valuable Improvement in Sash-Cord Guide-Blocks; and I do hereby declare that the following is a full, clear, and exact description of the construction and operation of the same, reference being had to the annexed drawings, making a part of this specification, and to the letters and figures of reference marked thereon.

Figure 1, of the drawing, is a longitudinal central section of my invention.

Figure 2 is a perspective view of the same.

Figure 3 is an end view of the same.

My invention relates to a means for supporting and guiding the balance-cords of windows; and consists, mainly, in the construction and novel arrangement of devices, whereby this object is satisfactorily attained.

The letter A, of the drawings, represents the guide-block, which is a cylindrical tube of hard wood, metal, glass, or any other suitable material.

The bore of the tube gradually expands toward each end, in such a manner that a section of the bore, taken through the axis of the cylinder, will give a curve, as indicated in fig. 1.

This sectional curve may be semicircular, elliptical, or of such other form as may be desired, but is the same for every element of the same block, so that when it is in place, it will be seen that it makes no difference which side is up, or which end is driven in first.

On the external surface of the block A, are one or more worms, b, formed, by which it is secured when driven into an auger-hole in the sash.

I do not claim, broadly, the screw-plug, when formed with a straight bore; but

What I claim as my invention, and desire to secure by Letters Patent, is—

The cylindrical tube herein described, having worms b, and isometrically-curved bore c, constructed and arranged to operate substantially as specified.

In testimony that I claim the above, I have hereunto subscribed my name, in the presence of two witnesses.

JAMES M. FORD.
